UNITED STATES PATENT OFFICE.

ELMER BEAVERS, OF LOS ANGELES, CALIFORNIA, ASSIGNOR, BY DIRECT AND MESNE ASSIGNMENTS, TO BEAVER SEAL JAR CAP COMPANY, OF NORRISTOWN, PENNSYLVANIA.

DESIGN FOR A FRUIT-JAR CAP.

Application filed October 29, 1920. Serial No. 420,556. Term of patent 14 years.

To all whom it may concern:

Be it known that I, ELMER BEAVERS, a citizen of the United States, residing at Los Angeles, in the county of Los Angeles and State of California, have invented a new, original, and ornamental Design for a Fruit-Jar Cap, of which the following is a specification, reference being had to the accompanying drawing, forming part thereof.

Fig. 1 is an edge view, Fig. 2 a plan view, and Fig. 3 an edge view taken at right angles to Fig. 1, of a fruit jar cap showing my new design.

What I claim is:

The ornamental design for a fruit jar cap, as shown.

In testimony whereof I affix my signature.

ELMER BEAVERS.
